UNITED STATES PATENT OFFICE.

EDGAR B. SYMONS, OF CHICAGO, ILLINOIS.

CRUSHING-MACHINE.

1,226,275.

Specification of Letters Patent. Patented May 15, 1917.

Application filed October 18, 1913. Serial No. 795,840.

To all whom it may concern:

Be it known that I, EDGAR B. SYMONS, a citizen of the United States, residing at Chicago, in the county of Cook and State of Illinois, have invented a certain new and useful Improvement in Crushing-Machines, of which the following is a specification.

My invention relates to improvements in crushing machinery and is illustrated in one form in the accompanying drawings, wherein—

Figure 1 is a vertical section;

Fig. 2 is a side elevation;

Fig. 3 is a vertical section of the crushing 15 disk means;

Fig. 4 is a diagrammatic section through the two crushing disks; and

Fig. 5 is a lay-out diagram illustrating the method of computing the areas of the 20 crushing zones.

Like parts are indicated by like letters throughout the several figures.

A is a main frame base. A² is an outer inclosing wall substantially circular and extending from the main frame base. A³ is an inner circular wall concentric with the wall and projecting upwardly from the main frame base A. A⁴ is an arched drive shaft bearing support forming in fact an increased continuation of the wall A³ and apertured at A⁵ to provide a communication between the area outside and inside of the circular wall A³. A⁶ is a bearing bracket mounted on and projecting above the support A⁴. A⁷ is an additional bearing bracket mounted on and projecting from the outer wall A² partially supported by the wall A³ which also contains the oil passage A⁸ leading from the outer end of said bearing 40 bracket to the interior of said wall A².

B is a bearing sleeve contained within the bearing bracket A⁶ and having on one end the thrust bearing flange B¹. B² is a bearing sleeve contained within the bearing bracket 45 A⁷ and having on its opposed end the thrust bearing B³. B⁴ is a drive shaft rotatably mounted in the bearing sleeve B². B⁵ is a pulley keyed to the shaft B⁴. B⁶ is a thrust bearing and oil retaining collar rigidly held 50 on the shaft B⁴ by the set screw B⁷ having two flanges B⁸ B⁹, one located inside and the other outside of the bracket wall A³, the flange B⁸ being in rotatable contact with the flange B³. B¹⁰ is a pinion keyed to the 55 shaft B⁴ between the bearings B¹ B². B¹⁰ is a gear keyed to the shaft B⁴ on its inner

end and having a hub B¹¹ in rotatable contact with the flange B¹.

C is a hollow cylindrical guide shaft or sleeve provided at its lower end with the 60 heavy flange C¹ pressed by the webs C² and resting upon the wall A³ being held in position thereby by the bolts and nuts as indicated. This flange C¹ is apertured as at C³ adjacent the bearing bracket A⁶ to make 65 room for the gear B¹⁰. C⁴ is an eccentrically bored cylindrical shaft rotatably mounted within the sleeve C and carrying on its lower end the driven gear C⁵ in mesh with the gear B¹⁰. This shaft is provided 70 at its lower end with a bearing plate C⁶ pinned in position for rotation with the shaft and resting upon a further bearing plate C⁷ pinned against rotation and mounted on the bosses C⁸ in the main base A. 75

D is an outer cylindrical shaft or sleeve mounted for rotation upon the sleeve and resting upon the annular ball bearing D¹ and flange C¹. This shaft D is provided with a heavy laterally extending flange D² 80 projecting outwardly from its upper end. The flange D² has downwardly depending about its periphery the collar D³ which carries the gear D⁴ in mesh with the pinion B¹⁰ and is provided with the annular rings 85 D⁵, D⁶, concentric with and one inside of and the other outside of the upper wall A². The flange D² has on its upper side a flat horizontal bearing surface D⁷ upon which is slidably mounted a circular wedged plate 90 D⁸ mounted on a shaft D⁹ which engages the eccentric bore in the shaft C⁴ and provided with an upwardly convex bearing surface D¹⁰ on its upper surface and a flat bearing surface D¹¹ on its lower side in opposition to the bearing surface D⁷. 95

E is a disk plate having on its lower side an upwardly concave bearing surface E¹ in opposition to the bearing surface D¹⁰ on the wedge D⁸ and having about its periphery a 100 spherical bearing surface E² in opposition to a similar spherical bearing surface on the flange D². E³ is a flat laterally distended crushing disk mounted on the disk plate E and held in position thereon by a ring E⁴ 105 which ring is in turn held in position by a holding screw E⁵. E⁶ is a material ring discharge guide resting upon the flange D² and having an inner extension projecting over the part of the disk plate E which extension is provided with an upwardly extended flange E⁷. The dust ring E⁸ mount-

ed on the disk plate E and held between it and the crushing disk plate E³ overlies and overhangs the flanges E⁷ to serve as a protection against the entrance of dust into the parts of the machine.

6 The upper disk supporting plate F carries a curved disk F¹ in opposition to the flat crushing disk E³. This disk F¹ is centrally apertured and provided with an upwardly and outwardly turned flange F² about said aperture. This flange is engaged by a collar F³ on a screw-threaded sleeve F⁴ which sleeve projects downwardly through the centrally apertured disk F and is held 10 down by the screw-threaded nut F⁵ which nut rests upon the upper surface of the plate F. The plate F is provided about its periphery with a cylindrical collar F⁶. This collar has extending from the upper surface 15 thereof the flange F⁷. The collar F⁶, it will be noted, is in screw-threaded engagement with an annular supporting ring F⁸ and set screws F⁹ are provided passing through the flange F⁷ and engaging the ring F⁸ to hold 20 the flange and ring in a fixed position each with respect to the other.

10 G G are guard and spacing sleeves resting upon the discharge guide E⁶ and supporting a guide ring G¹ upon which rests the supporting ring F⁸. G² G² are apertured lugs located about the periphery of the flange D² and outside of the collar D³ and beneath the guide ring E⁶. Through these lugs pass the bolts G³ which extend upwardly through the 15 spacing and supporting ring F⁸ and spacing and guard sleeves G and engage the supporting ring F⁸ and pass through the flanged ring G⁴ which overlies the flange G⁵ on the supporting ring F⁸ in such wise that the 20 springs G⁶ interposed between the spring ring G⁴ and the supporting ring F⁸ normally tend to yieldingly compress the supporting ring against the spacing sleeves G when the nuts G⁷ on the bolts G³ are manipulated 25 while still leaving the upper disk plate free to lift against the pressure of the springs along the bolts G³. It will be noted that the flange downwardly depending from the flanged ring G⁴ when the parts are in 30 position rests upon the ring G¹ so as to house the springs G⁶.

35 A housing comprising the cylindrical wall H and a flat upper wall H¹ comprises the rotary parts of the crushing machine. This housing is divided into two parts by an annular wall H² which overlies the guide ring G¹. The lower or material receiving part consists in an annular chamber surrounding the discharge aperture between the two 40 crushing disks bounded on its upper side by the rotating guide ring G¹ and the fixed guide ring H² on its outer side by the annular housing wall H, on its lower side by the flat annular wall H³ and the rotating 45 guide plate E⁶, on its inner side by the collar

H⁴. Inside of this annular chamber revolve the vanes H⁵ mounted on the guide ring E⁶, whose function is to convey material around said annular chamber to the discharge chute H⁷.

70 I is a feed hopper supported on a platform and turning into the guide chute I¹ discharging into a funnel I² which funnel is suspended by the bolts I³ beneath the spout I¹ and projects downwardly into the crushing chamber between the two crushing disks through the central aperture into the upper crushing disk.

75 In Fig. 3 I have shown a detail of means for holding the lower crushing disk in position. These means have been generally described. In detail, however, the crushing disk E³ as indicated, is centrally apertured. About the inside of this aperture is an inwardly extending flange K upon which rests 80 the flange ring E⁴. This flange ring is apertured at K¹, as indicated, and in this aperture rests the conical screw E⁵ slotted as at K². This conical screw is screw-threaded in the plate E. It is hollow having centrally 85 disposed therein the square hole K³ in which travels the square hub K⁴ projecting upwardly from the toothed locking plate K⁵ which is in opposition to the toothed plate K⁷ which is located in the aperture K⁸ and 90 held against rotation by the pins K⁹. The spring K¹⁰ yieldingly presses these locked plates together when the screw E⁵ is screwed down by any suitable means. When in position the conical plug K¹¹ protects the square 95 nut K¹² on the screw K¹³ which engages the hub K⁴. This plug is held in position by the cotter pin K¹⁴. When it is desired to remove the central holding screw it is necessary to 100 remove the cotter pin to lift out the conical plug, screw the supporting screws indicated down to the square hub to lift the upper toothed locking plate against the spring out of engagement with the other whereupon the 105 screw may be easily withdrawn.

110 Oiling is accomplished by the oil pump L which draws oil from the interior of the base, discharges it through the pipe L¹ into the space beneath the main shaft. This oil passes up through the conduit L² in the hollow shaft D⁹ and part of it passes between the shaft D⁹ and the sleeve C⁴. The oil passing between the shaft D⁹ and the sleeve C⁴ returns down between the shaft C⁴ and the sleeve D⁴ and between the sleeve C and the shaft D to the interior of the base lubricating these surfaces. Part of this oil may pass between the flange D² and the wedged plate D⁸ then returning to the conduit L² to the 115 interior of the base. The oil passing through the center of the shaft lubricates the upper surface of the wedged plate and also returns to the conduit L². The gears are lubricated by the splash. The same is true of the driving shaft and ball bearing. This oil pump is 120 125 130

driven from the shaft L^4 by the pulley L^5 and belt L^6 from the drive shaft B^4 as shown at B^6 . It is only necessary to drive the pump enough to force an excess volume of oil into the space beneath the thrust bearings since when this is done all the parts will be lubricated by the oil.

The housing H is held in position with respect to the crushing parts and the remainder of the mechanism by the columns M, M which rest upon the base A and are located outside of the housing A^2 .

Referring to the showing of the crushing disks as made in Fig. 4, it will be noted that there are formed between the disks F^1 and E^3 three crushing zones, namely a zone extending from x to y , a first fine crushing zone extending from the points y to z and a second fine crushing zone extending from the points z to q . The zone x to y is a coarse crushing zone wherein the material is held until it is reduced to a size smaller than the maximum opening between the point y and the flat surface of the disk E^3 . The two latter crushing zones it will be noted are but slightly different, the surfaces forming them being but very slightly divergent. They are so disposed that the material which is fed through them by centrifugal force from between the disks and across the disk E^3 , which I prefer to term a feed plate, will not have time to pass either from the point y to z or from the point z to q between crushing strokes. Thus every particle as it passes through will always under all circumstances invariably receive a crushing blow during its progress through each zone and this must always be the case, because if the rotational speeds rise or fall, the relation between the centrifugal force and the number of crushing strokes will be the same. Thus if the centrifugal force tends to drive the material through faster, the crushing strokes occur oftener and vice versa.

In order that as the material is fed by centrifugal force through the machine and no particle may be permitted to pass through either of the two outer crushing zones without being caught and crushed, it is necessary that the depth or width of the crushing zones be carefully correlated with respect to the relative angular velocity of the crushing disks and the eccentrics which cause the crushing blow to progressively travel about the peripheries of said disks and in order that this close correlation may be obtained, I have devised a graphic layout, which gives the desired result. We will assume a particle to be located along the line a, b at the point c . We then draw the circle c, j, h , which represents the inner boundary of the outer crushing zone, the particle being projected outwardly by centrifugal force along a tangent to the circle c, j, h , that is to say, along the line c, e . It should here be noted

that the relative travel of the eccentric and of the disk will previously have been fixed, such that the disk will travel through the arc b, e , while the eccentric travels through the arc b, d, e . The result of this will be that as the particle moves along the line c, e , with the velocity given it by the travel of the disk, it will shortly be intercepted by the crushing blow caused by the eccentric at the point e . We then draw the circle b, e, d , about the center a and this fixes the outer boundary of the outer crushing zone, because a particle starting thus at the inner boundary would be bound to be caught as it reached the outer boundary; thus no particle could be centrifugally forced through this zone, as here shown, without being caught and crushed. To fix the inner zone we will assume a particle at j , viz., the intersection of the line a, j, e , with the circle c, j, h , we then drop the perpendicular j, g to the base line a, b and draw the circle g, i to fix the inner boundary of the inner zone.

The use and operation of my invention is as follows:

The machine is driven from any suitable source of power by a belt not shown, applied to the driving pulley. The two pinions on the drive shaft rotate respectively the crushing head and the eccentric central sleeve, the rotation of the crushing head, containing as it does the two opposed crushing disks, tends to feed the material centrifugally outward toward and from between the peripheries of the crushing disks. The rotation of the eccentric sleeve in a direction opposite to that of the crushing head, causes the shaft downwardly projecting from the spherical disk wedge, to gyrate. The relative proportion of the parts is such that a number of gyrations of this shaft takes place during each revolution of the crushing head. Each of these gyrations causes the lower crushing disk to rock progressively on its central axis. This rocking movement travels about the periphery of the lower crushing disk somewhat in the manner of a sine wave, causing any given point in the lower crushing disk to alternately approach toward and recede from the upper crushing disk, giving a number of crushing strokes for each revolution.

When the disks recede one from the other, centrifugal force instantly feeds the material outward between them and as they approach this material is crushed and reduced into fine particles. This process continues until the finely divided material is ultimately discharged from the machine.

It will be noted that the outer edge of the upper disk is substantially flat, while the outer edge of the lower is very slightly cone-shaped so that as the lower disk rocks its surface may when in contact with the surface of the upper disk be absolutely parallel thereto. It is not necessary always to manu-

facture the lower disk in the cone shape, as experience shows that very soon it wears to that slight cone required. This cone is so slight, of course, that it does not appear on the drawing, but in order that best results may be obtained it must be present. Thus there is at all times during the crushing stroke an area of parallelism wherein the two crushing surfaces are parallel each to the other at the crushing point. This area of parallelism is of such width that no particle can, under any circumstances be fed through between the disks at such speed as to pass through this area without being caught and crushed at least once. The result of this arrangement is that no uncrushed particle can pass from the machine. This material which finally issues from between the crushing disks is discharged by centrifugal force out into the annular channel or ring surrounding the crushing head and thence is fed or carried by the vanes or paddles, carried by the crushing head to the discharge chute.

25 Owing to the large number of crushing strokes for each revolution, it is obvious that sufficiently great capacity may be obtained without unduly great rotational speeds, and it is sufficient to give the crushing disks a rotational speed only great enough to secure an adequate centrifugal feed.

The upper crushing disk is yieldingly held in position in relation to the crushing head. Its excursion or movement, however, with respect to the crushing head will be under ordinary circumstances but slight in proportion to the wabbling movement of the lower crushing disk and feed plate for crushing all but the finest, that is to say, crushing where the two disks or plates are never quite in contact, the movement of the upper plate will be but slight, as the tension of the springs will be so great that the material will normally be reduced before the plates yield against the springs. However, for the finest crushing it is necessary that the crushing disks be in contact when the machine is empty. Under these circumstances, of course, the springs will be constantly operated to permit the upper disk to play and leave room for the material to be crushed between the two disks, and this movement of the upper crushing disk permitted by the springs will be greater depending upon the amount of material fed through the machine. For very fine crushing and large capacity it will frequently be desirable to choke-feed the mill, and, of course, when this is done, the two disks may be separated by a considerable film of material in various stages of reduction. The springs, of course, must give to permit the two disks to separate to take care of this difficulty. The coarse thread engagement

65 between the annular supporting ring and

the cylindrical collar is provided to permit convenient and easy adjustment of the distance between the crushing disks, thus providing for varying of the size of the output. The central feed into the inner cavity, between the crushing disks, and the fact that the feed from then on is in a horizontal plane, provides for an even distribution of material about the entire periphery of the crushing disk during the crushing operation. The lower crushing disk is held on its supporting plate in any suitable manner as indicated, the centrally holding nut being provided with a slidably mounted tooth jaw clutch member held against rotation in the screw and in engagement with a similar member held against rotation in the disk. A yielding spring as indicated forces these two members together. A small cap screw provided, may be used to draw the clutch jaw upward against the spring pressure to release the two parts. The conical cap centrally located in the holding screw, covers this small cap screw to protect it.

The oiling device consists in the hollow supporting base which is at all times completely filled with oil. The oil is drawn from this base by a pump as shown, and forced into the chamber located immediately below the end of the supporting shaft. Thence it passes up into the interior of the shaft between it and the shaft, lubricating all the parts as indicated, some of it passing up as far as the gyrating wedge disk and finally passing down and returning to the base.

It will be noted that by this arrangement the oil never gets out of the oiling zone and no oiled parts or lubricated parts are ever exposed to the dust and dirt of the crushing zone.

Under ordinary circumstances when a granular product is desired, the distance between the two crushing disks will be such that they do not quite meet, and the measure of the product is in my machine the measure of the distance between the crushing disks at the time that crushing takes place, for no particle can get out of the machine until it has been reduced to or below that size. This effectively differentiates it from other types of centrifugal eccentric disk crushing machines wherein material when crushed feeds down until it is held by the crushing disks when farthest apart so that the limit to fineness of product is the extent of the opening when crushing is not taking place.

In case it is desired to produce a fine powder, it is only necessary to set the disks so that they touch and this will, of course, bring the springs slightly into play when the articles are banked up so as to prevent touching of the disks. In any event, the product will be a fine powder produced by the progressive crushing of the particles.

I have illustrated on a large scale a more or less modified form of my device, the modification being in that a plurality of fine crushing zones are provided so that 5 a reduction may take place more gradually, thus increasing the capacity of the machine and particularly permitting a very large reduction during the passage through the machine.

10 It will be understood that the central crushing zone where the disks are at a sharp angle one to the other feeds material to the fine crushing zone when that material has been reduced to such a size that it will 15 pass from between the two crushing disks as they open up or separate, and that is the law of a sharply inclined disk crushing machine, but from then on as the material passes into the fine crushing zone it is no 20 longer arrested by the disks as they separate but only arrested by the disks as they approach to crush, and this material which is fed from between a central coarse crushing zone travels outwardly into the fine 25 crushing zone and is projected tangentially across this zone by centrifugal force, being stopped only when the disks approach to crush. Thus all particles are arrested unless they are so small that they can pass between 30 the crushing disks when in the crushing position. Experience shows that when it is desired to reduce from comparatively large boulders down to a fine granular product or even a powder, it is much more satisfactory to do it first by the coarse crushing zone in the center and then by two or three progressively narrowing fine crushing zones about the periphery.

I claim:

40 1. A crushing machine comprising a pair of opposed rotating crushing disks inclined one to the other and rotating in unison, the effective crushing surfaces of said disks being parallel along a radial line and means 45 for changing the relative positions of the axes of said disks during rotation to move said radial line.

50 2. A crushing machine comprising a pair of opposed rotating crushing disks inclined one to the other and rotating in unison, the effective crushing surfaces of said disks being parallel along a radial line and means 55 for constantly gyrating the axis of one of said disks about the axis of the other to give said radial line a uniform uninterrupted movement about a fixed center.

3. A crushing machine comprising a pair of opposed rotating crushing disks inclined one to the other and rotating in unison, 60 the effective crushing surfaces of said disks being parallel only along a constantly progressing radial line.

4. A crushing machine comprising a pair of opposed rotating crushing disks inclined one to the other and rotating in unison, the 65

effective crushing surfaces of said disks being normally inclined each to the other but being parallel along a single constantly progressing radial line.

5. A crushing machine comprising a pair of opposed rotating crushing disks inclined one to the other and rotating in unison, the effective crushing surfaces of said disks being parallel only along a constantly progressing radial line and means for gyrating the axis of one of said disks about the axis of the other during rotation of the disks to move the position of said radial line of parallelism. 70

6. A crushing machine comprising a pair of opposed rotating crushing disks inclined one to the other and rotating in unison, the effective crushing surfaces of said disks being normally inclined each to the other but being parallel along a single constantly progressing radial line and means for gyrating the axis of one of said disks about the axis of the other during rotation of the disks to move the position of said radial line of parallelism. 75

7. A crushing machine comprising a pair of opposed rotating crushing disks inclined one to the other and rotating in unison, the effective crushing surfaces of said disks being parallel at one point only and means for constantly moving said point of parallelism about the peripheries of the crushing disks. 80

8. A crushing machine comprising a pair of opposed rotating crushing disks inclined one to the other and rotating in unison, the effective crushing surfaces of said disks being parallel at one point only and means for constantly moving said point of parallelism about the peripheries of the crushing disks in a direction opposite to the direction of the rotation of the disks. 100

9. A crushing machine comprising a pair of opposed rotating crushing disks inclined one to the other and rotating in unison, the effective crushing surfaces of said disks being parallel at one point only and means for constantly moving said point of parallelism about the peripheries of the crushing disks in a direction opposite to the direction of the rotation of the disks with a greater angular velocity than the angular velocity of the disks themselves. 110

10. A crushing machine comprising a pair of opposed rotating crushing disks inclined one to the other and rotating in unison and containing between the opposed surfaces thereof a plurality of annular separate crushing zones. 120

11. A crushing machine comprising a pair of opposed rotating crushing disks inclined one to the other and rotating in unison and containing between the opposed surfaces thereof a plurality of angular separate crushing zones, the opposed crushing sur- 125

- faces of one of said zones being always in parallelism at one point in the periphery thereof.
12. A crushing machine comprising a pair of opposed rotating crushing disks inclined one to the other and rotating in unison and containing between the opposed surfaces thereof a plurality of annular separate crushing zones, the opposed crushing surfaces of one of said zones being always in parallelism at one point in the periphery thereof and means for progressively moving said point of parallelism about the periphery thereof.
13. A crushing machine comprising a pair of opposed rotating crushing disks inclined one to the other and rotating in unison and containing between the opposed surfaces thereof a plurality of annular separate crushing zones, the opposed crushing surfaces of one of said zones being always in parallelism at one point in the periphery thereof and means for progressively moving said point of parallelism about the periphery thereof in a direction opposed to the direction of the rotation of the disks.
14. A crushing machine comprising a pair of opposed rotating crushing disks inclined one to the other and rotating in unison and containing between the opposed surfaces thereof a plurality of annular separate crushing zones, the opposed crushing surfaces of one of said zones being always in parallelism at one point in the periphery thereof and means for progressively moving said point of parallelism about the periphery thereof, at an angular velocity greater than the angular velocity of the disks.
15. A crushing machine comprising a pair of opposed rotating crushing disks inclined one to the other and rotating in unison and containing between the opposed surfaces thereof a plurality of annular separate crushing zones, the opposed crushing surfaces of one of said zones being always in parallelism at one point in the periphery thereof and means for progressively moving said point of parallelism about the periphery thereof in a direction opposed to the direction of the rotation of the disks at an angular velocity greater than the angular velocity of the disks.
16. A crushing machine comprising a pair of opposed rotating crushing disks inclined one to the other and rotating in unison, a plurality of separate crushing zones between said crushing disks and angles formed between the opposed surfaces in each of said zones being greater in the inner than in the outer zones.
17. A crushing machine comprising a pair of opposed rotating crushing disks inclined one to the other and rotating in unison, a plurality of separate crushing zones between said crushing disks and angles formed be-

tween the opposed surfaces in each of said zones being greater in the inner than in the outer zones, the opposed surfaces forming the outermost crushing zone being at the point of approach substantially parallel.

18. A crushing machine comprising a pair of opposed rotating crushing disks inclined one to the other and rotating in unison, a plurality of separate crushing zones between said crushing disks and angles formed between the opposed surfaces in each of said zones being greater in the inner than in the outer zones and means for gyrating the axis of rotation of one of said disks about the axis of rotation of the other to give the point of approach of the two disks an angular travel.

19. A crushing machine comprising a pair of opposed rotating crushing disks inclined one to the other and rotating in unison, a plurality of separate crushing zones between said crushing disks and angles formed between the opposed surfaces in each of said zones being greater in the inner than in the outer zones, the opposed surfaces forming the outermost crushing zone being at the point of approach substantially parallel and means for gyrating the axis of rotation of one of said disks about the axis of rotation of the other to give the point of approach of the two disks an angular travel.

20. A crushing machine comprising a pair of opposed rotating crushing disks inclined one to the other and rotating in unison, a plurality of separate crushing zones between said crushing disks and angles formed between the opposed surfaces in each of said zones being greater in the inner than in the outer zones and means for gyrating the axis of rotation of one of said disks about the axis of rotation of the other to give the point of approach of the two disks an angular travel in a direction opposed to the angular travel of the two disks.

21. A crushing machine comprising a pair of opposed rotating crushing disks inclined one to the other and rotating in unison, a plurality of separate crushing zones between said crushing disks and angles formed between the opposed surfaces in each of said zones being greater in the inner than in the outer zones, the opposed surfaces forming the outermost crushing zone being at the point of approach substantially parallel and means for gyrating the axis of rotation of one of said disks about the axis of rotation of the other to give the point of approach of the two disks an angular travel in a direction opposed to the angular travel of the two disks.

22. A crushing machine comprising a pair of opposed rotating crushing disks inclined one to the other and rotating in unison, a plurality of separate crushing zones between said crushing disks and angles

- formed between the opposed surfaces in each of said zones being greater in the inner than in the outer zones and means for gyrating the axis of rotation of one of said disks 5 about the axis of rotation of the other to give the point of approach of the two disks an angular travel at a greater angular velocity than the angular velocity of the two disks.
- 10 23. A crushing machine comprising a pair of opposed rotating crushing disks inclined one to the other and rotating in unison, a plurality of separate crushing zones between said crushing disks and angles 15 formed between the opposed surfaces in each of said zones being greater in the inner than in the outer zones, the opposed surfaces forming the outermost crushing zone being at the point of approach substantially 20 parallel and means for gyrating the axis of rotation of one of said disks about the axis of rotation of the other to give the point of approach of the two disks an angular travel at a greater angular velocity than the angular 25 velocity of the two disks.
24. A crushing machine comprising a pair of opposed rotating crushing disks inclined one to the other and rotating in unison, a plurality of separate crushing zones 30 between said crushing disks and angles formed between the opposed surfaces in each of said zones being greater in the inner than in the outer zones and means for gyrating the axis of rotation of one of said disks about the axis of rotation of the other to give the point of 35 approach of the two disks an angular travel in a direction opposed to the angular travel of the two disks at a greater angular velocity than the angular 40 velocity of the two disks.
25. A crushing machine comprising a pair of opposed rotating crushing disks inclined one to the other and rotating in unison, a plurality of separate crushing zones 45 between said crushing disks and angles formed between the opposed surfaces in each of said zones being greater in the inner than in the outer zones, the opposed surfaces forming the outermost crushing zone 50 being at the point of approach substantially parallel and means for gyrating the axis of rotation of one of said disks about the axis of rotation of the other to give the point of approach of the two disks an angular 55 travel in a direction opposed to the angular travel of the two disks at a greater angular velocity than the angular velocity of the two disks.
26. A crushing machine having a plurality of crushing zones arranged in series 60 and means for positively feeding material through them.
27. A crushing machine having a plurality of crushing zones arranged in series 65 and means for obtaining a plurality of reductions in one of them and a single reduction in another.
28. A crushing machine having a plurality of crushing zones arranged in series and means for obtaining a plurality of reductions in one of them and a single reduction 70 in another and means for feeding material positively through them.
29. A crushing machine having a plurality of crushing zones arranged in series 75 and means for obtaining a plurality of reductions in one of them and a single reduction in another and means for feeding material positively from the zone where the single reduction takes place to and through 80 the zone where a plurality of reductions take place.
30. A crushing machine having a plurality of crushing zones and means for holding the material in one of said zones until 85 it has been reduced to a certain predetermined size.
31. A crushing machine having a plurality of crushing zones and means for holding the material in one of said zones until 90 it has been reduced to a certain predetermined size and for subsequently feeding to the next zone.
32. A crushing machine having a plurality of crushing zones and means for holding the material in one of said zones until 95 it has been reduced to a certain predetermined size and means for feeding it freely to and through the next zone.
33. A crushing machine having a plurality of crushing zones and means for holding the material in one of said zones until 100 it has been reduced to a certain predetermined size and means for feeding it freely to and through the next zone and means for 105 simultaneously arresting and crushing the material as it passes through said latter zone.
34. A crushing machine comprising two opposed crushing members forming between 110 them a cavity having feed and discharge openings, means for conveying material away from the feed opening and toward the discharge opening at a predetermined rate of travel; and means for contracting said crushing cavity periodically to arrest the free travel of said material when same 115 has moved predetermined distances.
35. A crushing machine comprising two opposed crushing members forming between 120 them a cavity containing primary and secondary crushing zones; means for feeding material successively through said secondary zones at a predetermined rate of travel; and means for contracting each zone at predetermined intervals to arrest and crush the material therein.
36. A crushing machine comprising two opposed crushing members forming between 125 them a cavity having feed and discharge 130

openings, said cavity comprising a primary crushing zone adjacent to said feed opening and a secondary zone adjacent to said discharge opening, said secondary zone being spaced to allow when expanded a free passage therethrough of material from said primary zone; means for expanding said secondary zone; means for feeding said material in continuous travel from said primary zone into and through said secondary zone when expanded; and means for contracting said secondary zone to interrupt said free passage therethrough of material by compression of same.

37. A crushing machine comprising two opposed rotating disks forming between them a crushing cavity, one of said disks constituting a feed plate for conveying material through said cavity at a predetermined rate of travel; means for oscillating one of said disks to contract said cavity at intervals timed with reference to travel of said material through said cavity whereby said material may be arrested and crushed when it has moved predetermined distances.

38. A crushing machine comprising two disks forming between them a cavity having feed and discharge openings, said cavity comprising a primary zone adjacent to the feed opening and surrounded by secondary zones; means for expanding said secondary zones to allow the free travel therethrough of all material discharged from said primary zone; means for feeding material from said primary zone in continuous travel at predetermined rate into and through said secondary zones; and means for contracting successively each portion of said secondary zones at intervals timed with reference to said predetermined rate of travel of material.

39. A crushing machine comprising two opposed crushing disks, one of said disks constituting a feed plate adapted to convey material to be crushed in continuous travel between said disks and at a predetermined rate; means for imparting to one of said disks a closing movement periodically to interrupt the free travel of said material and to crush said material at predetermined points on its line of travel.

40. A crushing machine comprising two opposed crushing members, one of which is adapted to approach and recede from the other, said members inclosing between them a cavity allowing in a substantial proportion thereof the free travel of material therethrough except when said cavity is contracted by the crushing movement given one of said members.

41. A crushing machine comprising two opposed crushing members forming between them a cavity having feed and discharge openings, said cavity containing a primary

zone adjacent to said feed opening and a series of secondary zones; means for expanding said secondary zones to allow free travel of material there-through; means for conveying material from the feed opening toward the exit opening at a predetermined rate of travel; and means for contracting said secondary zones successively in each part thereof to arrest and crush said material in each secondary zone.

42. A crushing machine comprising two opposed crushing members forming between them a cavity having feed and discharge openings, containing a primary crushing zone adjacent to the feed opening and a series of secondary zones; means for discharging the material from said primary zone and for feeding same through said secondary zones at a predetermined rate of travel; means for expanding said secondary zones to permit the free travel there-through of material discharged from said primary zone; and means for contracting said secondary zones at predetermined intervals to arrest and crush said material in each secondary zone.

43. A crushing machine comprising two opposed crushing members forming between them a cavity containing a centrally located coarse-crushing zone surrounded by a series of fine crushing zones; means for feeding the material from said coarse crushing zone into and through said fine crushing zones; means for expanding said fine crushing zones to allow the free travel there-through of all material discharged from said coarse crushing zone; and means for contracting said fine crushing zones to arrest and crush in each fine crushing zone the material passing there-through.

44. A crushing machine comprising two opposed crushing members forming between them a crushing cavity; means for opening or expanding successively portions of said cavity to allow the free travel of material there-through; means for feeding in continuous travel through expanded portions of said cavity material to be crushed; means for arresting said free travel of said material by compression thereof at predetermined intervals.

45. A crushing machine comprising two opposed crushing members forming between them a crushing cavity containing a series of crushing zones; means for feeding the material in unrestricted travel through some of said zones, and for arresting said material by compression thereof in each of said zones.

46. A crushing machine comprising two opposed disks forming between them a crushing cavity containing crushing zones; said disks rotating in unison and one of said disks constituting a whirling feed plate

- for feeding the material to be crushed through said zones; means for vibrating one of said disks to arrest at predetermined intervals the travel of said material by compression thereof whereby the material is arrested and crushed in each of said zones.
47. A crushing machine comprising two opposed crushing members forming between them a cavity containing a series of fine crushing zones, each of which allows, when expanded, the free passage therethrough of material fed there-into from the adjacent zone; means for expanding said zones; means for feeding successively through each zone material to be crushed; and means for contracting each fine crushing zone to crush material passing therethrough.
48. A crushing machine comprising two opposed crushing members forming between them a cavity containing crushing zones through which all material to be crushed therein may pass freely when said zones are expanded, combined with means for oscillating one of said members to expand and contract said zones.
49. A crushing machine containing a crushing cavity and comprising means for passing material along in said cavity at an approximately predetermined rate of travel, combined with means for arresting said material by compression thereof at intervals timed with reference to its rate of travel, thereby allowing material to move distances, approximately predetermined, between compressions.
50. A crushing machine having a plurality of crushing zones arranged in series, means for positively feeding material through them and means for positively crushing the material at least once during its passage through each of said zones.
51. A crushing machine having a plurality of crushing disks inclined one to the other, a crushing zone interposed between said disks, means for positively and freely feeding material through said zones and means for crushing it at least once during its passage through said zones.
52. A crushing machine comprising a plurality of rotating crushing disks, a plurality of crushing zones arranged in series between them and means for positively feeding material through said zones.
53. A crushing machine comprising a plurality of rotating crushing disks, a plurality of crushing zones arranged in series between them and means for positively feeding material through said zones and means for crushing the material at least once during its passage through each of said zones.
54. In a crushing machine a rotating disk and means for rotating it and a support for the disk and means for giving it a gyroscopic movement separate from the disk.
55. In a crushing machine a rotating disk and means for rotating it and a support for the disk and means for giving it a gyroscopic movement separate from the disk, said means comprising an eccentric bearing and a connection between it and the support.
56. In a crushing machine a rotating disk and means for rotating it and a support for the disk and means for giving it a gyroscopic movement separate from the disk, said means comprising an eccentric bearing and a connection between it and the support and means for rotating said bearing.
57. In a crushing machine a hollow shaft, a flange projecting therefrom, a pair of opposed rotating crushing disks supported one of them rigidly upon said shaft, a support for the other one slidable upon said flange.
58. In a crushing machine a hollow shaft, a flange projecting therefrom, a pair of opposed rotating crushing disks supported one of them rigidly upon said shaft, a support for the other one slidable upon said flange, said support being free to slide upon said flange.
59. In a crushing machine a hollow shaft, a flange projecting therefrom, a pair of opposed rotating crushing disks supported one of them rigidly upon said shaft, a support for the other one slidable upon said flange and means for giving said support a gyroscopic movement upon said flange.
60. In a crushing machine a fixed bearing sleeve, two shafts one of them hollow and bearing upon the outside of said sleeve, the other bearing on the inside of said sleeve, crushing disks mounted on said shafts and means for operating said shafts to cause said disks to alternately approach toward and recede from one another.
61. In a crushing machine a fixed bearing sleeve, two shafts one of them hollow and bearing upon the outside of said sleeve, the other bearing on the inside of said sleeve, crushing disks mounted on said shafts and means for operating said shafts to cause said disks to alternately approach toward and recede from one another and means for rotating said shafts to cause said disks to progressively approach toward and recede from one another and to cause a discharge of material from between the disks by centrifugal force.
62. In a crushing machine a fixed bearing sleeve, a hollow shaft surrounding and guided by said sleeve, a crushing disk supported on said hollow shaft, a crushing disk interposed between the hollow shaft and the disk which is mounted on it and means contained within said fixed bearing sleeve for

moving said second disk toward and from the first disk along a constantly progressing angularly moving radius.

68. In a crushing machine a fixed bearing sleeve, a hollow shaft surrounding and guided by said sleeve, a crushing disk supported on said hollow shaft, a crushing disk interposed between the hollow shaft and the disk which is mounted on it and means contained within said fixed bearing sleeve for moving said second disk toward and from the first disk along a constantly progressing angularly moving radius, said means comprising an eccentric member within the hollow bearing sleeve.

64. In a crushing machine a crushing disk, a floating supporting disk therefor, a portion of the back side of which forms the segment of a sphere and the portion of the bounding periphery of which forms a segment of a separate sphere.

65. In a crushing machine a supporting shaft, a flange perpendicular thereto, said flange being bounded by a wall, the inner surface of which is formed by a segment of a sphere inclined to the surface of the flange, a floating plate bounded by a spherical surface concentric with and in engagement with the bounding surface of the wall, a lenticular tilting member having a surface in slidable engagement with the surface of the flange and a spherical surface in engagement with the back side of the floating plate, the back side of the floating plate being bounded by a spherical surface concentric with the spherical surface of the tilting member.

66. A crushing disk for crushing members and the like having a flat annular outer crushing surface and a curved disk-shaped annular inner crushing surface.

67. A crushing disk for crushing members and the like having a flat annular outer crushing surface and a curved dish-shaped annular inner crushing surface, said disk being centrally apertured.

68. In a crushing machine a crushing head comprising a flange and annular ring supported on said flange, a crushing disk carried by said annular ring and yielding means for pressing said annular ring toward said flange.

69. In a crushing machine a crushing head comprising a flange and annular ring supported on said flange, a crushing disk

carried by said annular ring and adjustable yielding means for pressing said annular ring toward said flange.

70. In a crushing machine a crushing head comprising a flange and annular ring supported on said flange, a crushing disk carried by said annular ring and yielding means for pressing said annular ring toward said flange, said crushing means being adjustably mounted in said annular ring.

71. In a crushing machine a crushing head comprising a flange and annular ring supported on said flange, a crushing disk carried by said annular ring and adjustable yielding means for pressing said annular ring toward said flange, said crushing means being adjustably mounted in said annular ring.

72. In a crushing machine a cylindrical housing open at the top, a shaft rotatably mounted in said housing, a flange carried by the shaft perpendicular to the axis of the housing, a wall projecting downwardly from the flange concentric with the housing to close the space between the flange and the housing.

73. In a crushing machine a cylindrical housing open at the top, a shaft rotatably mounted in said housing, a flange carried by the shaft perpendicular to the axis of the housing, a wall projecting downwardly from the flange concentric with the housing to close the space between the flange and the housing, said wall be curved at its bottom and extending downward both within and without the wall of the housing to complete the closure.

74. A crushing machine having two rotating, crushing disks inclined one to the other, means for causing said disks to approach to and recede from one another along a substantially radial line, the angular movement of such line being such that it makes a complete revolution in less time than it takes a particle to pass through the crushing zone formed between the crushing surfaces under the influence of centrifugal force.

In testimony whereof, I affix my signature in the presence of two witnesses this 14th day of October, 1913.

EDGAR B. SYMONS.
